(57) **CLAIM**

The ornamental design for a model vehicle upper suspension arm as shown and described.

DESCRIPTION

FIG. 1 is an upper, left, front perspective view of a model vehicle upper suspension arm showing our new design; FIG. 2 is an upper, right, rear perspective view thereof; FIG. 3 is a lower, right, front perspective view thereof; FIG. 4 is a lower, left, rear perspective view thereof; FIG. 5 is a front elevation view thereof; FIG. 6 is a rear elevation view thereof; FIG. 7 is an upper plan view thereof; FIG. 8 is a lower plan view thereof; FIG. 9 is a right-side elevation view thereof; and, FIG. 10 is a left-side elevation view of the model vehicle upper suspension arm.

Only the left-side model vehicle upper suspension arm is shown. The right-side model vehicle upper suspension arm is a mirror image of the shown model vehicle upper suspension arm.

1 Claim, 7 Drawing Sheets
